WILLIAM WRIGHT, OF CHICAGO, ILLINOIS, ASSIGNOR TO E. PAYSON SMITH, OF SPRINGFIELD, ILLINOIS.

COMBINED CHEEK PLATE AND DRAFT-KEY ANCHOR.

Application filed August 6, 1925. Serial No. 48,448.

My invention relates to an integral or single piece structure constituting a cheek plate adapted to be secured to the outer side of the center sill of a railroad car at the draft rigging and coupler ends thereof whereby the slotted ends of the center sill are reenforced and proper guideways for the draft keys of the coupler and draft rigging are provided; while at the same time 10 also constituting means for locking or anchoring the draft keys against accidental removal and loss.

My invention has for its object the provision of a casting or single member adapted 15 to be riveted or properly secured to the vertical side of a center sill member lengthwise thereof and throughout that part of the draft rigging where the usual draft keys are located and have movement in a direction 20 lengthwise of the center sill; one purpose of my invention being to obviate the necessity of employing and riveting different members to the center sill, serving separately as a reenforcing member or cheek plate and a 25 draft key retainer or anchor; my invention therefore provides means which eliminates the extra time and labor otherwise required in securing separate elements to the center sill which also involve the placing of additional rivet holes in the center sill members and a consequent weakening and therefore 30 undesirable condition not in keeping with standard railway construction.

The objects and advantages of my invention 35 will be more readily comprehended from the detailed description of the accompanying drawing, wherein:—

Figure 1 is a plan view of a portion of the center sill of a car, the coupler, portions of 40 the draft rigging and draft keys, illustrating the application of my improved cheek plate and draft key anchor.

Figure 2 is a side elevation of a center 45 sill with my improved cheek plate and draft key anchor; the coupler being omitted.

Figure 3 is a vertical sectional view taken on the line 3—3 of Figure 2 looking in the direction of the arrows.

Figure 4 is a detail perspective view of 50 the main or cheek plate portion of the device.

In the drawing, the center sill members are shown at 10, 10 arranged in the usual parallel spaced relation, between which the draft rigging is mounted; a portion of the 55 draft rigging yoke being shown at 11; while

12 indicates the coupler, the shank whereof is disposed between the center sill member and the yoke 11. The center sill members, draft rigging yoke and the coupler shank are provided with the usual slots disposed 60 longitudinally of said members and adapted to be brought into register to receive the usual draft keys shown at 13, 13. As the draft rigging forms no part of my invention, a detailed description and more specific illustration thereof need not be entered into. 65

My invention contemplates the use of a single casting or plate 14 of length sufficient to extend beyond the opposite ends of the draft key slots in the center sill member so 70 as to reinforce the latter; the casting or plate 14 comprising the main base portion 15 adapted to lie flush against the center sill member 10 and to be riveted or otherwise secured thereto as for example by means of 75 rivets which pass through the rivet receiving apertures shown at 16. The ends 17 of the base portion 15 are arranged substantially at right angles and disposed outwardly 80 a distance beyond the vertical planes of the heads 18 of the draft keys 13 when the latter are in place. These end portions 17 have their immediate ends preferably reenforced by having the same disposed toward the opposite end of the cheek plate and substantially parallel with the base portion 15 as 85 shown at 19 in Figure 4. The base portion 15 is also preferably provided with a slot or slots 20, 20 to correspond with the slots in the draft rigging and the center sill so as to 90 receive the draft keys 13, 13; the base portion 15 of the cheek plate member being preferably provided with a reenforcing web 95 21 extending lengthwise of the plate and about the slots 20 as clearly shown in Figure 4.

The portion of the cheek plate 14, intermediate of the slots 20, 20, namely at a point intermediate of the ends of the cheek plate, is shown provided with an integrally formed, 100 outwardly disposed skeleton lug or bracket portion 22 which extends laterally outward preferably to the same extent as the end portions 17, 17.

The end portions 17, as well as the intermediate bracket lug 22, may be provided with suitable reenforcing webs as at 23 so as to provide a strong rigid structure. 105

The end portions 17, at points adjacent to the outer ends thereof, are each provided 110

with a vertically disposed slot 24; while the bracket lug 22 may either be in the nature of a laterally disposed U-shaped lug or in the nature of a solid lug provided with a slot 5 therethrough of configuration similar to the slots 24. That is to say, the bracket lug 22 is intended to have an opening therethrough at least at a point in alignment with the openings 24 in the end portions 17, in order 10 that a latch bar or member 25 may be inserted longitudinally through the slots 24 in the end portions 17 and through the bracket lug 22 to extend lengthwise of the plate 14, with the latch member arranged in a plane 15 slightly beyond the heads 18 of the draft keys 13 and therefore transversely of the path of the draft keys, as clearly shown in Figures 1 and 3.

The latch member 25 consists of a plate 20 or flat bar of comparative thickness, with the major portion of width slightly less than the vertical dimensions of the slots 24 and of length slightly greater than the distance between the end portions 17, 17 of the cheek 25 plate member 14. The latch member or plate 25 has each end preferably provided with a depending lip or projection 26, and with one end of the latch member on its upper edge also provided with the enlarged 30 portion or shoulder 27 so that the vertical dimension of the end of the latch member with the shoulder 27 is substantially equal to the vertical dimension of the elongated slot 24 in the end portion 17 of the cheek 35 plate. Vertical movement of the latch member or plate 25 at this end of the cheek plate is therefore prevented.

When the latch member or plate 25 has been inserted in place, the depending portions or lips 26 will depend beneath the lower 40 edges of the slots 24 and prevent longitudinal movement of the latch member or plate 25; it being apparent that the end provided with the shoulder 27 will prevent further 45 inward longitudinal movement of the latch plate or member 25 because the distance from the top of the shoulder portion 27 to the bottom of the lip or projection 26 at that end of the latch member is greater than the 50 vertical dimension of the slot 24 in the end portion 17 of the cheek plate.

In order to prevent possibility of the latch member or plate 25 shifting longitudinally toward the end provided with the shoulder 55 27 and therefore becoming displaced, I prefer to provide one of the outwardly disposed portions of the cheek plate, as for example the intermediate bracket lug portion 22 of the cheek plate, with an aperture 28 and also 60 to provide the latch member or plate 25 with a similar opening which will be in register with the opening 28 when the latch member or plate is in proper position. The registering openings in the latch plate and bracket lug receive a suitable split pin or

cotter as at 29 in Figure 1 which will lock the latch member or plate 25 against any longitudinal movement in the direction of the shouldered end 27 of the member 25.

The present method of securing the draft 70 keys in place consists in providing the tapered or tail end of the draft key with an opening through which is inserted a cotter or split pin. These pins, by reason of the constant shifting of the draft keys, are readily 75 sheared off because they are brought up against the sides of the center sill member or the reenforcing plates secured to the center sill where the pins are subjected to enormous 80 shearing strains. When the cotter pins are 85 sheared off, the draft keys tend to move longitudinally in the direction of the head end and as a result they soon become displaced, the coupler and other elements are 90 allowed to drop out of place, causing a 95 disarrangement of the draft rigging and often producing serious results.

With my invention, the center sill is provided 100 with a reenforcing cheek plate which also constitutes means whereby the draft keys may be securely locked in place against undesirable longitudinal movement and accidental removal; while at the same time a structure is provided which will permit ready access to be had to the draft keys in 105 the event that removal of the draft key is desired for any purpose.

I have shown and described what I believe 110 to be a simple embodiment of my invention; having described the same in terms employed merely as terms of description and not as terms of limitation; structural modifications being possible and may be made without, however, departing from the spirit 115 of my invention.

What I claim is:—

1. A device of the character described, comprising a single piece metallic plate slotted longitudinally and adapted to be secured to the center sill of a railroad car, the ends of the plate being disposed laterally toward one side of the plate and having aligned openings therethrough, and a bar or rod insertible through said aligned openings lengthwise of the plate so as to be disposed across the slotted portion thereof.

2. A combined cheek plate and draft key anchor, comprising a plate adapted to be secured to a car center sill and extend lengthwise thereof beyond the opposite ends of the draft key slots in the center sill, the plate being slotted to register with the draft key slots in the center sill and having its ends bent outwardly to a distance beyond the horizontal plane of the draft key head, the ends having openings therethrough, and a bar or rod insertible through said openings and provided with abutting surfaces for holding the bar or rod against longitudinal movement.

3. A combined cheek plate and draft key anchor, comprising a plate adapted to be secured to a car center sill lengthwise thereof and surrounding the draft key slots in the center sill, said plate being slotted at points in register with the draft key slots in the center sill, the ends of the plate being disposed outwardly in parallel relation with each other and having registering openings, 10 and a bar insertible through the registering openings to extend lengthwise of the plate, the ends of the bar being provided with projections adapted to engage with the ends of the plate to prevent longitudinal movement 15 of the bar.

4. A combined cheek plate and draft key anchor, comprising a slotted plate adapted to be secured to a car center sill lengthwise of

the draft key slots therein, the ends and an intermediate portion of the plate being 20 formed to extend outwardly and provided with registering openings, a bar insertible into said openings and disposed across the paths of the draft key heads, and means for holding said bar in place.

5. A combined cheek plate and draft key anchor, comprising a slotted plate having rivet-receiving holes, outwardly disposed ends, and a transverse web intermediate of its ends, both ends and said web being 30 provided with aligned openings therethrough, a bar insertible into said openings so as to be disposed across the path of the draft key heads, and means for holding the bar in place.

WILLIAM WRIGHT.
